WINDOW WEDGE

Hubert O. Carroll, Painesville, Ohio

Application February 2, 1939, Serial No. 254,258

5 Claims. (Cl. 292—342)

In windows of the sliding type, it is customary to fit the sashes in the stops initially as tightly as possible while still permitting movement. When the windows are painted the sashes stick 5 tightly and it is quite common that the stress which is incurred in efforts at opening and closing the window, causes distortion-damage to the sash resulting in springing of the sash, and often starting strain-cracks in the glass. After the 10 paint is worn down, the more or less exposed wood easily absorbs moisture, and on recurring rainy spells the sticking difficulty recurs and further strain-damage results. If the sashes are fitted loosely in the stops on the other hand, the 15 window rattles in windy weather, and even with the most efficient sash-closures it is impossible to lock the sashes sufficiently against the stops to keep out drafts. In accordance with the present invention however, a window construction 20 may now be had in which a sash may be fitted loosely, such as to facilitate easy movement and completely avert distortion-damage to the sash from strains resultant from sticking, and at the same time the sash may be held tightly against 25 its stop to prevent rattling and drafts.

To the accomplishment of the foregoing and related ends, the invention, then, comprises the features hereinafter fully described, and particularly pointed out in the claims, the following 30 description and the annexed drawing setting forth in detail certain illustrative embodiments of the invention, these being indicative however, of but a few of the various ways in which the principle of the invention may be employed.

35 In said annexed drawing:

Fig. 1 is an inside perspective view of a window in accordance with the invention; Fig. 2 is a view from the outside; Fig. 3 is an enlarged sectional view taken on a plane substantially indicated by the line III—III, Fig. 1; Fig. 4 is a similar section taken on a plane substantially indicated by the line IV—IV, Fig. 1, and of course a corresponding view in Fig. 2; Fig. 5 is an enlarged fragmentary detail elevational view of the 45 operating mechanism as would appear looking toward the left hand on Fig. 1; Fig. 6 is a vertical sectional detail through the cam plate and shoe within, in one position, viz. with the parts as shown by Fig. 5 in full line; Fig. 7 is a similar 50 view with the parts in position as indicated in dotted line in Fig. 5; and Fig. 8 is a transverse sectional detail on a plane substantially indicated by line VIII, Fig. 2.

In a window having a frame 2, and sashes 3, 4, 55 sliding therein, a central stop 5, Fig. 3, and out-

side and inside stops 6, 7, Figs. 4 and 3, are provided respectively, and therewith means for forcing each sash into tight relation, this involving in general a cam plate having a cam surface which is on an incline with relation to the axis 5 of the stop while a shoe carried by the cam plate and having a portion riding the cam surface, is provided with means resiliently urging the shoe to a remote portion of the cam surface, and means operated by the sash tends to push the 10 shoe to the other portion of the cam surface. The mechanism is of particular usefulness with lower sashes inasmuch as these are generally the worst offenders where undue tightness or undue looseness occurs, and as shown in Fig. 1, it is 15 desirable to have a cam plate 9 at each side, as on the inner stop 7. A complete complement will however desirably involve a corresponding pair for the upper sash, as shown more fully in Fig. 2. The stops need not be close against the 20 sashes. In fact, it is advantageous to have them with ample space and irrespective of paint and dirt accumulation the sashes will operate easily and freely. As shown in Fig. 3, the cam plate 9 is of angular form and is set on a slight cut-out 25 in the inside stop 7 and may be suitably fastened, as by screws 10. Carried by the cam plate 9 is a shoe 11. The cam plate 9 has an inclined slot 12, shown particularly clearly in Figs. 6 and 7, and the cam shoe 11 is provided with stirrups 13 30 so as to slidably straddle the inner wing of the cam plate, as is seen more clearly in Fig. 3, and a pin 14 extends through the cam slot 12 and rides on its surfaces, being secured in the stirrups 13 of the shoe, as by rivet-heading. Desirably, 35 the pin 14 projects through externally sufficiently to be provided with a head 15 for actuation, as will appear more clearly hereinafter. As thus seen, looking at Fig. 3, the cam plate 9 stationary on the frame or stop, allows the cam shoe 11 to 40 travel back and forth on the plate as a base, such travel being in general in direction of alinement with the sash, but by reason of the cam slot 12 the shoe is in a position back from the sash at one end of its excursion and at the other end 45 of its excursion is thrusting against the sash and pushes the sash against the stop 5. Normally, the shoe is urged into its back position, as indicated in Fig. 6, by suitable resilient means, such as a spring 16. Such spring, within the cam 50 plate and cam shoe is wholly out of the way and protected. The camming shoe is operated automatically by the sash, and for this the sash may be provided with an actuator. Desirably this may be a member 17, Fig. 5, as a projection from 55
